SOLVENT APPLICATOR FOR IMPRINTING MACHINES

Joseph A. Weber, Prospect Heights, Ill.

Application December 5, 1950; Serial No. 199,263.

2 Claims. (Cl. 118—268)

1

This invention relates to a new and improved solvent applicator for use in imprinting machines.

A principal object of this invention is the provision of solvent applying means in an addressing machine constituting an improvement in the device of my copending application for patent entitled "Addressing Machine," Serial No. 63,421, and filed December 3, 1948, now Patent No. 2,542,443.

An important object of this invention is to provide a simple and effective means for moistening an envelope or card in an addressing machine employing a hectographic ink transfer process.

Another important object of this invention is to supply a yieldable wick means depending within a well on the platen surface of the imprinting machine and adapted to transfer solvent solution from the well to the top surface of an envelope or card as it is slid across the top or bed of the machine to a position beneath the imprinting head.

A further important object of this invention is the provision of means for maintaining a well filled with liquid ink solvent.

Another and still further important object of this invention is to provide a wick type applicator normally disposed in a well of liquid solvent and preferably resting on a wick contained within the well and said applicator arranged and constructed to be yieldable upwardly a limited distance for the purpose of depositing a strip of liquid solvent on the top surface of an envelope or card to receive the printing transfer.

Other and further important objects shall become apparent from the disclosures in the following specification and accompanying drawing.

In the drawing:

Figure 1 is a perspective view of the addressing machine incorporating the solvent applicator of this invention.

Figure 2 is a front elevational view of a portion of the device as shown in Figure 1.

Figure 3 is a top plan view of the device of Figure 2.

Figure 4 is a sectional view taken on the line 4—4 of Figure 3.

Figure 5 is a sectional view taken on the line 5—5 of Figure 3.

As shown in the drawings:

The reference numeral 10 indicates generally a supporting base for the addressing machine incorporating the wick type moistener of this invention. The supporting base includes a bed or top surface 11 which has a guide rail 12 extending along the rear edge thereof. A depressed portion 13 of the bed 11 is equipped with a sponge rubber strip 14 constituting the platen of the addressing machine. My copending patent application, Serial No. 63,421, mentioned above describes the operation of a pressure head 15 in conjunction with the platen. The pressure head comprises an operating arm or handle 16, hinged at the rear of the supporting base 10 at 17 for

2

vertical swinging movement toward and away from the sponge rubber platen 14. A hectographic master tape roll 18 is carried on a supply spool 19 and is wound up on a take-up spool 20 positioned at and on the forward end of the handle 16.

A superstructure 21 is rigidly mounted with the base support 10 and carries a wick holding bracket 22, riveted or otherwise fastened to the structure 21 at 23. A portion 24 of the bracket 22 is disposed horizontally and parallel to the bed 11 of the addressing machine. A downwardly and under curved end 25 of the bracket 22 joins the parallel portion 24 and carries a flat spring 26 by means of rivets or the like 27 on the under curved portion of the bracket. A felt or other fibrous material wick 28 is fastened by rivets or screw fastening means or the like 29 to the flat leaf spring 26 and by means of adjusting screws 30 the spring 26 is yieldable upwardly a predetermined distance. A second leaf spring 26a is mounted on the underside of the felt wick 28 and is held fixed with respect to the spring 26 by means of the rivets or screw fastening means 29. The lower end of the spring 26a is foreshortened as shown at 26b leaving the lower end of the felt wick 28 exposed.

A first adjusting screw 30 threadedly engages the horizontally disposed portion 24 of the bracket 22 and abuts the flat spring 26 at a position where it lies in contact with the spring 26a closely beneath the attachment of the springs to the bracket by the attaching rivet 27. A thumb engaging knurled head 31 on the screw 30 provides for vertical adjustment of the screw 30 and thus the vertical position of the spring arm fulcrum may be adjusted as desired. A second adjusting screw 32 threadedly engages the portion 24 of the bracket 22 and is equipped with a round head 33 at its lower end. The head 33 is preferably spaced a distance above the spring 26 an amount equal to the desired upward displacement of the spring wick. A thumb engaging knurled head 34 is provided on the upper end of the screw 32 and permits manual adjustment of the vertical position of the screw 32 with respect to the wick holding bracket 22 and the wick. As shown in Figure 2 the head of the screw 32 is spaced above the spring 26 an amount sufficiently great so that the wick may be swung upwardly away from the bed 11 to permit passage of envelopes or cards between the bed and the wick.

A well 35 is located beneath the surface of the bed 11 in vertical alignment with an opening 35a in the bed. The well and opening are positioned 55 in transverse alignment with the wick 28 and also the sponge rubber platen 14. A reservoir bottle 36 carries liquid solvent and is provided with an under cap 37 for a closure of the open bottom of the bottle 36. A tubular discharge conduit 38 forms a part of the underside of the cap 37 and projects downwardly into a tubular well 39 as best shown in Figures 4 and 5. A

shoulder 39a on the forward side of the well 39 is for the purpose of positioning the well with respect to the bed. A bracket 40 extends across and engages the undersides of the well like container 39 and the well 35 thus holding them both up against the base support 10 by means of a screw 41. An inlined cut-off 42 of the lower end of the tubular discharge 38 rests on the bottom 43 of the tubular well 39. A nipple fitting 44 in the front side of the bottom of the well 39 provides a connecting means for a flexible conduit 45. The conduit 45 thus joins the fitting 44 at one end and its other end is fastened to a nipple fitting 46 in the corner of the rear and side of the bottom of the wick well 35 in the central portion of the platen bed. Liquid solvent is thus transmitted from the reservoir 36 to the wick well 35. A block type wick 47 is positioned in the well 35 and by means of capillary action carries the liquid ink solvent upwardly to the top portion of the wick. Thus the spring held wick 28 is normally held in direct contact with the well wick 47 causing the wick 28 to be charged with solvent.

As best shown in Figure 1, an operator slides a card or the like 49 across the bed 11 of the imprinting machine against the opposing action of the spring held wick 28 causing the wick 28 to be swung upwardly out of contact with the wick 47 in the liquid solvent well 35 and by reason of the flat spring 26 the felt wick 28 is urged downwardly against the card 49. As shown in the dash line position of the wick 28 in Figure 4 at 50 the wick rides on the top surface of the card imparting a strip of liquid solvent thereto. The strip of moistened surface lies directly over the sponge rubber platen 14 whereupon a downward movement of the pressure head 15 causes the hectographic master roll 18 to be pressed against the solvent impregnated portion of the card 49. The card is thus imprinted with a transfer of a portion of the hectographic ink from the master roll.

The wick 28 of this invention thus provides positive and adequate moistening of the card or envelope to be imprinted without the aid of complex rolls or other moving parts. The spring held wick 28 lying on the wick in the well 35 on the surface of the bed 11 automatically performs the moistening of the material to be imprinted and automatically reenters the well 35 and reengages the wick 47 for restoring liquid thereto as soon as the initial card or envelope passes therethrough to the imprinting position on the platen 14. The wick is thus always charged with sufficient liquid solvent to properly impregnate the succeeding card or envelope to be imprinted.

In the operation of the device of this invention the first adjusting screw 30 acts as a fulcrum for the flat spring 26 and the second adjusting screw acts as a limit device for the upward swinging movement of the wick 28. It is thus apparent with the present apparatus the moistening of the top surface only of the card or envelope to be imprinted is accomplished with the supply of liquid solvent located in a well on the surface of the bed 11 whereas heretofore complex means were required to transfer the liquid solvent from a low storage position to an upper position over the material to be imprinted. In combination with the limit adjusting screw 32 which compensates for various thicknesses of paper stock being imprinted the moistening apparatus of this addressing machine functions to paint a strip of solvent in the right position on the material to

be imprinted only on the top surface thereof and as a normal function of the machine the wick is continually recharged with liquid solvent after the passage through the machine of the card or other paper to be imprinted. The manual sliding of the card 49 across the bed 11 from the left side thereof as viewed in Figure 1 to the right side automatically causes the wick to rise out of the well 35 out of contact with the well wick 47 and deposit liquid solvent on the surface thereof whereupon when the card arrives at its imprinting position on the platen 14 it is ready to receive a transfer of the hectographic ink from the master roll.

I am aware that numerous details of construction may be varied throughout a wide range without departing from the principles disclosed herein and I therefore do not propose limiting the patent granted hereon otherwise than as necessitated by the appended claims.

What is claimed is:

1. A liquid applicator comprising a support, said support having therein a transversely extending liquid well, a longitudinally extending superstructure carried on said support above said liquid well, a leaf spring fastened to said superstructure and extending in a longitudinal direction, a longitudinally extending yieldable wick fastened to and forming a part of said leaf spring and disposed beneath said superstructure, said yieldable wick having an end thereof depending within said well, and a liquid reservoir adjacent said support and having means arranged and constructed to supply liquid to said well, a wick disposed within said well and beneath the top surface thereof, whereby when sheet material is slid across the said support it is coated on its top side with a liquid as it raises the yieldable wick out of the well from a position in engagement with the wick within the well whereafter the yieldable wick rides on and across the top surface of the sheet material, a vertically adjustable screw means threadedly engaging said superstructure adjacent the well engaging portion of the leaf spring and yieldable wick for regulating the amount of upward swinging thereof, and a fulcrum forming adjustable screw threadedly engaging said superstructure and abutting said leaf spring and yieldable wick at the end thereof adjacent said superstructure and away from said well.

2. A device as set forth in claim 1 in which said yieldable wick includes a fibrous material and said leaf spring includes vertically spaced apart portions disposed above and below the fibrous material, and the lower of said leaf spring portions being foreshortened so that the fibrous material is uncovered at its lower end to be recharged with liquid from the well wick.

JOSEPH A. WEBER.
